THEODOR VON BAUER, OF TAUTENBURG, IN THURINGIA, GERMANY, ASSIGNEE TO
BERNHARD ZWILLINGER, OF NEW YORK, N. Y.

COKE-OVEN.

1,253,445.

Specification of Letters Patent. Patented Jan. 15, 1913.

Application filed July 11, 1913. Serial No. 778,427.

To all whom it may concern:

Be it known that I, THEODOR VON BAUER, a citizen of the German Empire, and residing at Tautenburg, in Thuringia, Germany, have invented certain new and useful Improvements in Coke-Ovens, of which the following is a specification.

My invention relates to a recuperative coke-oven which is adapted to yield by-products and which comprises heating walls having horizontally divided flues to which preheated air and heating gas are supplied according to need from the front of the furnace with or without the use of a blast and with or without fractional working as desired.

One of the objects of my invention is to supply to the oven air and gas which are regulatable according to requirements, are mixed in the theoretical proportions best for combustion and are considerably preheated, and to obtain thereby a much higher heat economy, a smaller consumption of heating gas and larger surplus of gas than heretofore.

Other objects of my invention are to improve the manufacture of coke with or without the simultaneous recovery of by-products, to obtain an increased out-put thereof, and to improve the quality of the same.

Furthermore my object is to operate the oven with a direct or indirect supply of gas or a number directly and the other ovens indirectly, or to operate the ovens by a fractional method by which the rich gas obtained in the earlier stages of coking is separated from the poor gas given off at a later period of coking. In the direct mode of operation the gases evolved from the coal pass directly from the coking chamber into the heating flues without being conducted to the condensing plant. In the indirect mode of operation the gases evolved from the coal pass through the condensing plant, etc., and after being deprived of the by-products the gases go to the heating flues and the surplus gas is stored. In the mixed mode of operation a number of ovens of a battery are worked by the direct mode and the remaining number either by the indirect or fractional mode.

Another feature of my invention lies in the construction and in the process by means

of which the air and the gases for heating the oven are mixed, supplied and burned so that the heat increases in a downward direction from the roof to the bottom and so that the temperature at the upper levels can be regulated and controlled and kept down whereas the temperature at the lower levels of the heating flues is raised. By this means a decomposition of the gases evolved from the charge is avoided. For if the heating flues of the oven and the walls of the coking chamber were heated uniformly the top layer of coke will prematurely carbonize and the ascending gases evolved from the lower layers of coal are partially decomposed when they strike the bare top and side walls of the oven, or when passing through the upper bed of hot coke. Another advantage obtained by progressively heating the charge in a downward direction is due to the increasing density of the coal at the lower levels due to the pressure from the weight of the upper layers on the layers below. In order to coke the entire charge uniformly it is desirable to provide an increased heat for coking the denser layers.

In the oven constructed in accordance with my invention the upper passages of the heating flues being horizontal and the lower passages vertical, I am enabled to regulate and control and moderate the heat in the upper flues at the same time increasing the heat in the lower flues to the greatest amount desired.

In further accordance with the invention, with a view to obtaining very nearly the said theoretical proportions best for combustion and to secure the desired temperature at the corresponding level, rows of shallow boxes filled with pieces of chamotte are arranged, which rows of boxes I now arrange as partition walls, in order that the air-gas mixture may be forced through them by the blast and in order to bring about a more perfect combustion owing to the narrow ramifying passages between the chamotte.

In addition to this, I make further constructional improvements in the oven, which are hereinafter pointed out and described.

One illustrative embodiment of my invention is represented by way of example in the accompanying drawing wherein:

Figure 1 is a transverse section of the

oven, one-half of the section being taken through a coking chamber and the other half of the section being taken through a heating wall between the coking chambers.

5 Figs. 2 and 3 are sections on lines 2—2 and 3—3 in Fig. 4, respectively.

Fig. 4 is a sectional plan of a portion of a furnace, the section being taken through the horizontal ducts for connecting the coking chambers through the interior of the heating walls.

Fig. 5 is an enlarged detail of a portion of the vertical flues in the heating walls.

Fig. 6 is a vertical cross-section through 15 the air ducts, vertical heating flues and the oven chamber.

Fig. 7 is a vertical cross section of the heating wall through the heating channel carrying rows of shallow boxes.

20 Fig. 8 is a horizontal section through the horizontal heating flues above the supports for the chamotte beds of Fig. 1.

Fig. 9 is a side view partly in section showing the long slide valve.

25 Fig. 10 is a cross section of Fig. 9.

Fig. 11 is a section showing the short slide valve.

Referring to the drawing, the gas-air mixture which is in combustion in the upper 30 flue *e* passes through the short vertical passages *f*, which are in the intermediate wall below the flue *e* and serve as distributors, to the second horizontal flue *g*. This flue *g* obtains from the nozzles of the vertical 35 pipes before the heads of the oven walls new supplies of gas and air, and the jets of gas and air so supplied impinge at a right angle on the combustion mixture which is streaming vertically from the ducts *f*.

40 The augmented mixture now passes over the top of the division wall *h* and, by descending by the passage shown at the left of this wall, arrives in the third flue *i*. The division wall extends from side to side 45 of the heating wall—this term being applied to the complete structure between adjacent coking chambers—and contains two longitudinal ducts, one for gas and one for air, each duct having a number of downwardly directed branches or apertures. The air and gas ducts are shown in Figs. 6 and 50 7. The air duct *u* communicates with the recuperator *u* and the gas duct *d* with the gas main *d*. The flue *i* thus obtains new supplies of gas and air in a vertical direction 55 from the apertures in the division wall *h* and in a horizontal direction from the said vertical pipes.

Air and gas mixed in the correct theoretical proportions for combustion, and pressed 60 through a porous plate and ignited develop, as is well known, higher temperatures than it is possible to obtain in the usual manner.

65 The application of such pressures as would

here be needed is however out of the question owing to the construction of the coke-oven. Moreover in coke-ovens temperatures so high as to call into requisition some very special refractory material for this purpose 70 are not necessary.

My invention, having for an object to so arrange that the theoretical air requirements are met as far as possible, is however able to employ the usual refractory materials and 75 regulating means.

To this end, shallow boxes having stone bottoms *St* perforated at 102 to admit the air and gases and filled with pieces of chamotte *Sch* are built in below the flue *i* and each row 80 of these boxes serves as a division wall forming the lower boundary of flue *i*.

The gas-air mixture, comprising the gradually augmented supplies of air and gas, is now compelled to penetrate the narrow 85 ramifications between the pieces of chamotte filling the boxes.

Owing to that intimate mixture of gas and air which is so obtained, the combustion air is considerably better utilized so that 90 a smaller consumption of gas and air is required, a heating gas of a higher calorific value is obtained from the charge in the coking chamber, shorter paths for the gases are required and consequently the space requirements are much reduced.

From the apertures in the bottoms of the boxes the combustion mixture passes to the vertical flues *k*, which take this mixture to the bottom of the combustion chamber, and 100 from there the mixture passes under the bottom of the coking chamber *Ok* through the sole channel *l* and so reaches the recuperator. Between the vertical flues *k* are air ducts *Lp*, in which the preheated air which 105 rises from the collecting flue *v*, from the recuperator flues *v*, is still further heated, and, passing out through openings *o* above the pieces of chamotte, combines with the yet uncombined constituent of the gaseous 110 mixture.

The hot gases therefore flow from the highest flue *e* to the bottom of the oven, obtain on the way repeated accessions of air and gas, and the whole mixture becomes intimately mixed, as described, in the chamotte boxes which simultaneously act as heat reservoirs. Hence while this occurs, the temperature continually increases from the upper portion of the oven downwardly and can 115 be exactly regulated.

For this reason one well-known defect is obviated, viz. the defect that the upper, loose portions of the coking coal are gasified prematurely, the consequence being that the 120 quality of the distillate is likely to be impaired owing to decomposition.

The recuperator supplies the combustion air to the heating walls partly from below them and partly from the front walls of the 130

oven. The flues of the recuperator are divided in accordance with this distribution of the air, and it is possible to regulate, both in quantity and temperature, the air to be supplied to the various places of combustion.

The construction of the recuperator is seen from the drawing. The vaulted culvert *a* in the foundation is free from piping and return nozzles, and in this culvert are arranged the slide-valves *b* and *c*. By means of the slide-valve *b* air enters the flues of the recuperator *v* and passes onto the uppermost flue *v*₁ serving as the collecting flue for the warm air.

This highest flue *v*₁ distributes the previously warmed air in the air ducts *Lp* which, as stated, have outlets in the direction of the vertical heating flues *k*.

20 The slide-valve *c* serves for supplying air to the flues *u* of the recuperator from which flues the air passes to the vertical pipes located at the front wall of the oven, which pipes have branches, not shown, connected with the upper portion of the heating walls.

25 In order to be able to supply air from the blower to one or both of the bifurcating air flues *v*, *u* of the recuperator, two air culverts *y*, which are connected to one blower, are built in the foundation masonry.

30 These culverts are connected by short vertical ducts with the flues *v*, *u* in which ducts are located iron slide-valves which can be reached through the apertures behind the slide-valves *b*, *c*.

35 The air from the blower can now clearly go one way (through the flues *v*) to the air ducts *Lp* and another way (through the flues *u*) to the vertical pipes. By adjusting the valve *m*, the products which flow away under the oven-bottom can be conducted, in known manner, either into the flues of the recuperator or directly through the bridging flue *p* to the main culvert *o* for the dis- charged gases.

40 Devices are known for working the oven directly or indirectly by the aid of connecting flues which are under the control of closure valves and are located between the coking chambers and the heating walls.

45 In the arrangements heretofore, however, the closure valves and the flues leading thereto must, when working indirectly, be closed to prevent gas from passing over from the coking chambers to the heating walls, and when, on the other hand, the change had to be made to direct working, all the valves must be torn out of place. Such work is troublesome and tedious and the 50 chamotte valves are damaged thereby.

The gases from the coking chambers can be conducted extremely simply and in a manner adapted to the desired mode of working, when, as my invention provides, 55 the flues connecting the oven-chambers to

the heating walls are constructed as follows:—

The coking chambers have, as seen from Figs. 1 and 4, a number of charging apertures *m*, which are arranged in rows transverse to each of the coking chambers. Between each of these transverse rows of apertures is arranged a double row of vertical ducts *D*, and the pairs of ducts alongside one another are connected alternately to the coking chambers and the heating walls. The adjacent ducts in each row are also connected by a horizontal duct *r* in a zig-zag manner, as is clear from Fig. 4. In each horizontal duct *r* I arrange a valve in the form of a slide *Um* which can be inserted from the top of the oven, and I can thus close any duct connecting the coking chamber to the heating wall. Owing to the zig-zag arrangement of horizontal ducts, I can thus connect a given coking chamber with the heating wall located either at the right or at the left of it.

The said slide moves in a guide 100 built into the masonry 101, and has like its guide 90 a flange, whereby the two form an air-tight joint. I preferably employ two slides one of which (*Um*) extends to the bottom of the horizontal duct and the shorter one (*Umb*) only down to the bottom of the 95 guide.

When the one or the other of these slides is lowered until its flange fits well against the flange of its guide, no leakage can occur from the horizontal duct and no luting 100 is required.

When the long slide is lowered there is gas on both sides of it. Since the distillation gases flow away toward the outlet *sc* where they are sucked away by the shaft, 105 and since the gases in the heating flues also flow away from the slide valve, the latter is protected from over-heating.

The shorter slide, when in place, is entirely surrounded by brickwork, and consequently hot gases cannot come into contact with it at all.

Applying the direct mode of operation the short slide "Umb" is used, leaving open the connecting cross channel *r* of the coking 115 chamber and heating flues.

The indirect mode of operation is carried out by using the long slide *Um* which closes the connecting cross channel and compels the gases to flow to the condensing plant. 120

The fractional mode of operation is carried out by using the long slide during the "rich gas period" and the short slide when the "poor gas period" begins—in one or a number of ovens.

The mixed mode of operations is carried out in such a manner that while using the long slide in one or a number of ovens, the short slide is also in commission in one or a number of ovens in an oven battery.

If it is desired to always operate the oven by the indirect mode of operation, thus taking out the gases through the conduit *Sc* in Fig. 1 to the condensing plant, it is preferable to plug the openings *D* by means of stones *q* (Fig. 1). The stone *s* is a cover stone.

I claim:—

1. A coke oven in which the temperature increases from the upper portion of the oven downwardly, having in combination heating walls which are divided by horizontal division walls so as to provide horizontal flues, means for supplying air and gas to the upper flues from the front of the oven, the horizontal division wall below the highest flue having a plurality of vertical ducts arranged side by side, which serve as distributors, the next horizontal flue receiving the gaseous mixture from the distributors, means for supplying air and gas from the front of the oven to said next horizontal flue, a division wall over which the resultant mixture is guided, said wall being provided with horizontal ducts for air and gas and downwardly directed apertures connected to said ducts, and a third horizontal flue receiving the discharge from said ducts.
2. A coke oven having in combination heating walls divided by horizontal division walls so as to provide horizontal flues, means for supplying air and gas to the upper flues from the front of the oven, the horizontal division wall below the highest flues having a plurality of vertical ducts arranged side by side, which serve as distributors, the next horizontal flue receiving the gaseous mixture from the distributors, means for supplying air and gas from the front of the oven to said next horizontal flue, a division wall over which the resultant mixture is guided, said wall being provided with horizontal ducts for air and gas and downwardly directed apertures connected to said ducts, a third horizontal flue receiving the discharge from said ducts, and a system of vertical flues receiving the discharge from the third horizontal flue, the parts of the oven being so constructed and arranged that the temperature of the oven increases downwardly.
3. A coke oven having in combination heating walls divided by horizontal division walls so as to provide horizontal flues, means for supplying air and gas to the upper flues from the front of the oven, the horizontal division wall below the highest flue having a plurality of vertical ducts arranged side by side, which serve as distributors, the next horizontal flue receiving the gaseous mixture from the distributors, means for supplying air and gas from the front of the oven to said next horizontal flue, a division wall over which the resultant mixture is guided, said wall being provided with horizontal ducts for air and gas and down-

wardly directed apertures connected to said ducts, a third horizontal flue receiving the discharge from said ducts, a system of vertical flues receiving the discharge from the third horizontal flue, and means for supplying fresh air to said system of vertical flues.

4. A coke oven having in combination heating walls divided into horizontal flues, means for supplying air and gas from outside of the oven to the upper flue, a division wall for distributing the gaseous mixture discharged by the upper flue, a row of perforated boxes containing refractory material forming part of said division wall, said material serving to mix the air and gas passing through them, a row of vertical flues receiving the mixture passing through said boxes, said vertical flues being perforated at the bottom to discharge the hot combustion products, and a recuperator for receiving the discharge.

5. A coke oven having a heating wall provided with horizontal division walls, said division walls dividing said heating wall into a plurality of combustion flues, vertical flues arranged beneath the lower horizontal combustion flue formed by said division walls, air ducts between said vertical flues and communicating with them, a recuperator, means for delivering the air from said recuperator, through said air ducts so as to additionally heat the air above the temperature produced by the recuperator.

6. A coke oven having heating walls provided with horizontal division walls, vertical flues arranged beneath the horizontal flues formed by said division walls, air ducts between said vertical flues, a recuperator, means for delivering the air from said recuperator, through said air ducts so as to additionally heat the air above the temperature produced by the recuperator, a plurality of boxes containing refractory material arranged between the horizontal flues and the vertical flues, and means for guiding the air from the air ducts through said boxes into the vertical flues.

7. A recuperative coke oven having in combination horizontal flues and vertical flues receiving the discharge from the horizontal flues and a sub-divided recuperator, one part of which supplies the preheated air to the horizontal flues and the other part supplies highly preheated air to the vertical flues.

8. A recuperative coke oven having in combination horizontal flues and vertical flues receiving the discharge from the horizontal flues and a sub-divided recuperator, one part of which supplies the preheated air to the horizontal flues and the other part supplies highly preheated air to the vertical flues, the two parts of the recuperator being provided with valves for the admission of the air to be preheated and means for

supplying gas to the horizontal flues through a pipe at the outside of the oven.

9. In a coking oven the combination of a heating wall which is horizontally divided, means for supplying air partly from below and partly from in front of the oven, a plurality of vertical gas supply ducts arranged in rows, the ducts in each row being alternatively connected to a coking chamber 10 and a heating wall and a plurality of horizontal ducts connecting two adjacent vertical ducts in a row together with valves for closing said ducts.

10. A coking oven having in combination 15 a coking chamber, a heating wall for said chamber, a horizontal division wall in the upper portion of said heating wall so as to form a horizontal combustion flue and a plurality of vertical combustion flues communicating with said horizontal combustion flue.

11. A coking oven having in combination 20 a coking chamber, a heating wall for said chamber, a horizontal division wall in the upper portion of said heating wall so as to form a horizontal combustion flue, a plurality of vertical combustion flues communicating with said horizontal flue, means for supplying heated fresh air and gas to the 25 horizontal flue and means for supplying preheated air to said vertical flues.

12. In a coke oven the combination of a horizontal combustion flue, vertical passages arranged along the length of said flue and 30 acting as distributors of the gas to said flue and means for supplying air and gas in a direction substantially at right angles to said vertical passages.

13. In a coke oven the combination of a 35 horizontal division wall, said wall being provided with transverse openings and means for supplying air and gas to the combustion flue beneath said wall in a direction substantially at right angles to the direction 40 of the openings.

14. In a coke oven the combination of a 45 coking chamber, a heating wall provided with a heating passage, a plurality of ducts in the roof of the oven for connecting the 50 coking chamber with the heating passage at intervals along the length of the coking chamber, an outlet conduit connecting said coking chamber with a gas condenser and a plurality of short and long slides, operated 55 from the roof of the oven, for said ducts whereby the coking chamber may be connected at one or more points to the heating passage or the products from the coking chamber may be led to the condensing plant.

60 15. In a coke oven the combination of a plurality of coking chambers side by side, a heating wall between each pair of coking chambers, said heating wall containing a heating passage, a plurality of openings in 65 the roof of each coking chamber and a plu-

rality of openings in the heating passages, ducts for connecting an opening in the roof of a coking chamber with an opening in the heating wall and additional ducts for connecting an opening in the roof of the neighboring coking chamber with an opening in the 70 said heating wall and slides in said ducts so that the gases may pass from adjacent coking chambers into the heating passage between said chambers when the slides are 75 opened.

16. In a coke oven the combination of a coking chamber, one or more charging openings for said chamber, a heating wall on each side of said chamber provided with a 80 heating passage, a plurality of ducts in the roof of the oven for connecting the coking chamber with said heating passages at intervals along the length of the coking chamber, said ducts lying in rows transversely to the 85 length of the oven and arranged at intervals between said charging openings, an outlet conduit connecting said coking chamber with a gas condenser and means manually operated from the roof of the oven for controlling said ducts whereby the coking chamber may be connected at one or more points 90 to the heating passages or the products from the coking chamber may be led to the condensing plant. 95

17. In a coke oven the combination of a coking chamber, one or more charging apertures for said coking chamber, a heating wall provided with a heating passage, a plurality of ducts in the roof of the oven for 100 connecting the coking chamber with the heating passage at one side of the coking chamber at intervals along the length of the coking chamber, a plurality of ducts in the roof of the oven for connecting said coking 105 chamber with the heating passage at the other side of the said coking chamber at intervals along its length, said ducts lying in rows transverse to the coking chamber and located between said charging apertures, an 110 outlet conduit connecting said coking chamber with a gas condenser and means manually operated from the roof of the oven for controlling said ducts whereby the coking chamber may be connected at one or more 115 points to the said heating passages or the products from the coking chamber may be led to the condensing plant.

18. In a coke oven, the combination of a coking chamber, a heating wall provided 120 with a heating passage, a plurality of ducts in the roof of the oven for connecting the coking chamber with the heating passage at one side of the coking chamber at intervals along the length of the coking chamber, a 125 plurality of ducts in the roof of the oven for connecting said coking chamber with the heating passage at the other side of the said coking chamber at intervals along its length, charging apertures in the roof of the oven 130

independent of and located between said ducts, an outlet conduit connecting said coking chamber with a gas condenser and sliding plates manually operated from the roof of the oven for controlling said ducts whereby the coking chamber may be connected at one or more points to the heating passage or the products from the coking chamber may be led to the condensing plant.

In testimony whereof, I affix my signature ¹⁰ in the presence of two witnesses.
